(57) **CLAIM**

The ornamental design for a bottle with stopper, as shown and described.

DESCRIPTION

FIG. 1 is a top front perspective view of a bottle with stopper showing a first embodiment of the design.

FIG. 2 is a front view of thereof, the left, right, and rear views being the same.

FIG. 3 is a top view thereof.

FIG. 4 is a bottom view thereof.

FIG. 5 is a top front perspective view of a bottle with stopper showing a second embodiment of the design.

FIG. 6 is a front view thereof, the left, right, and rear views being the same.

FIG. 7 is a top view thereof; and,

FIG. 8 is a bottom view thereof.

The dashed lines in the drawings depict portions of the bottle with stopper that form no part of the claimed design.

1 Claim, 8 Drawing Sheets
